SOLE-MOLDING MACHINE

Albin C. Eek, Webster Groves, Mo., assignor to
United Shoe Machinery Corporation, Fleming-
ton, N. J., a corporation of New Jersey

Application March 30, 1944, Serial No. 528,692

13 Claims. (Cl. 12—21)

This invention relates to sole-molding machines of the type comprising cooperating upper and lower sole-molding forms adapted to operate upon a sole before the sole is incorporated in a shoe. More particularly, the invention relates to a novel sole-gaging device for such machines.

In machines of the type referred to a gage is commonly provided for positioning the sole longitudinally with respect to the lower form by engagement with the heel end of the sole as the sole is being laid upon the lower form by the operator. To adapt the machine for certain types of molding it is sometimes necessary to employ a lower form of such a shape that when the sole is resting on the form the heel end of the sole will be elevated more or less with respect to the adjacent surface of the form. For use in gaging the locations of soles with respect to such forms it has been proposed to employ a yielding sole gage which extends between the forms and is normally supported a short distance above the lower form, the gage being adapted to be depressed with the heel end of the sole as the forms are being brought into cooperative molding relation. With such a sole gage it may sometimes happen, in presenting the sole to the machine, that the heel end of the sole will be forced rearwardly between the gage and the lower form, in which event not only will the gage be prevented from performing its sole-positioning function but it will be so located above the sole that it will be pressed into the sole during the molding operation, thereby causing the sole to be mutilated.

One object of the present invention is to insure against liability of any sole being presented to the machine in such a way as to render the sole-gaging means inoperative or to cause the sole to be damaged in the molding thereof.

With this and other objects in view, the invention provides a novel gaging device which is constructed and arranged as will be hereinafter described and claimed.

The invention will now be explained with reference to the accompanying drawings, in which

Fig. 1 is a view in vertical longitudinal section of a sole molding machine provided with my improved sole-gaging device;

Fig. 2 is a view in vertical longitudinal section and on a somewhat enlarged scale of a portion of the machine showing the upper and lower molding forms in their initial positions and showing a sole resting upon the lower form in a position determined by the sole-gaging device;

Fig. 3 is a view similar to Fig. 2 but on a still

larger scale and showing the positions of parts when the sole is being molded;

Fig. 4 is a perspective view of the gaging device; and

Fig. 5 is a plan view of the sole-gaging device and a portion of the lower form showing a sole in position upon the form.

The illustrated sole-molding machine is provided with two sets of cooperating sole-molding forms, the upper forms being stationary and the lower forms being reciprocable simultaneously in opposite directions toward and from the upper forms and also being reciprocable horizontally toward and from positions of vertical alignment with the upper forms. Both lower forms are mounted and actuated in the same manner and the sole-gaging devices associated with the lower forms are duplicates of each other. Accordingly, only a single set of forms and a single sole-gaging device have been illustrated in the drawings.

Referring to Fig. 1 of the drawings, the upper form 10 is removably secured upon a carrier 12 which is supported upon a stationary crosshead 14. The lower form 16 is removably mounted upon a slide 18 which reciprocates in a horizontal guideway formed on a vertically movable crosshead 20. Vertical reciprocating movements are imparted to the crosshead 20 from a crank shaft 22 by means of a link 24 and toggle levers 26. Horizontal reciprocating movements are imparted to the slide 18 by means of a bell crank 28 which is mounted on the crosshead 20 and has one arm connected to the slide 18 by means of a link 30, the other arm of the bell crank being connected by a link 32 to an arm 34 integral with a rockshaft or sleeve 36 journaled on the frame 38 of the machine. An arm 40 extends rearwardly from the rockshaft 36 and is connected by a spring 42 with the stationary crosshead 14. During the up-and-down movements of the crosshead 20 the bell crank lever 28 is rocked and imparts inward and outward movements to the slide 18. The inward movement of the slide 18 is limited by a crosspiece 44 at the rear end of the guideway for the slide 18. The form-carrying slide corresponding to the slide 18 on the opposite side of the machine is actuated by a similar bell crank which is connected to another arm rigid with the rockshaft 36, the arrangement of bell cranks and slides being such that the reciprocating movements of the slides take place during the lower half of the reciprocations of the crosshead 20, and its corresponding crosshead, in each direction.

55 An improved sole-gaging device is associated

with each of the lower molding forms, one of these devices being indicated at 46 in Fig. 1. The gaging device 46 is carried by an arm 48 which is pivoted at 50 to the upper side of a slide 52 mounted upon a horizontal guide rod 54. The guide rod 54 is secured at its opposite ends to brackets 56 formed on a carrier 58 that is clamped by a cam 60 to the form-carrying slide 18. To adjust the gaging device 46 to different sizes of soles, means is provided for moving the slide 52 lengthwise of the rod 54, this means comprising actuating mechanism 62 carried by the slide 18 and connected by a rod 64 with a projection 66 on the slide 52. The gaging device associated with the lower form at the opposite side of the machine is a duplicate of the device 46 and mechanism corresponding to that above described is employed for supporting and adjusting it.

All the parts thus far described, with the exception of the sole-gaging device 46 and the pivoted arm 48 (and the corresponding parts at the opposite side of the machine), are substantially the same as described in the patent to Preble No. 1,004,075, dated September 26, 1911.

The sole-gaging device 46, in accordance with the present invention, comprises two parts, viz., a rigid gage plate 70 and a spring finger 72 (Figs. 2 to 4). The rear portion of the gage plate 70 is fixedly secured by screws 74 to the pivoted arm 48 and the rear portion of the spring finger 72 is riveted at 76 to the upper side of the plate 70. The gage plate 70 is slotted at 78 (Fig. 4) to receive the forward portion of the spring finger 72 which is offset downwardly with respect to the rear portion thereof and extends below the gage plate. The slot 78 is open at its forward end and at opposite sides of the slot the gage plate 70 is recessed to receive the heel end of the sole which is to be molded. The edge portions which define the recess in the gage plate are upturned to form narrow flanges 80 which are slightly less in width than the thickness of the sole to be molded and are laterally curved to conform to the arcuate curvature of the edge of the heel portion of the sole. The gage plate is thus adapted to determine the lengthwise relation of the sole to the lower molding form. The flanges 80 of the gage plate extend forwardly far enough to engage the opposite lateral edges of the sole substantially at points where the arcuate curve of its heel portion merges with the less sharply curved lateral edge portions thereof, thus enabling the flanges 80 to perform also the function of determining, with a substantial degree of accuracy, the angular relation of the sole to the lower molding form. The forward extremity of the spring finger 72 is upturned to form a flange 82 which is substantially the same width as the flanges 80 on the gage plate 70 and which occupies a position of alignment with the rear extremities of the gage plate flanges. The portion of the spring finger 72 near the base of the flange 82 rests upon the upper surface of the lower form 16 and thus the spring finger serves to hold the gage plate 70 yieldingly a short distance above the form.

As shown, the lower molding form 16 is provided with an upward convexity 84 for cooperating with a corresponding concavity 86 in the upper form 10 to impart an arched formation to the shank portion of the sole. When a sole to be molded is laid upon the lower form by the operator the sole (which is at that time in a flat condition) will ordinarily be supported with its toe end resting upon the forward portion of the form and with its shank portion upon the con-

vexity 84, the sole being positioned substantially as illustrated by the sole S in Fig. 2. The sole S is of the type commonly known as a "spring heel" sole, the heel portion of the sole being thickened by having a heel lift S' cemented thereto, and my improved gaging device is particularly adapted for use in connection with soles of this type. With the sole S positioned as shown in Fig. 2, it will be noted that the heel end of the sole is held somewhat above the rear portion of the form. The gage plate 70 is held by the spring finger 72 in the proper spaced relation to the form 16 to engage the rear edge of a sole thus positioned and thereby to determine the lengthwise and angular position of the sole with respect to the form. The sole is laid upon the form when the latter is in the forward position shown in Fig. 1 and the form is then moved rearwardly into a position of vertical alignment with the upper form 10, after which the lower form is raised to press the sole against the upper form. During the final stage of the upward movement of the form 16 the flanges 80 of the gage plate 72 will engage the upper form and, when the lower form has reached its uppermost position and the sole is being pressed into conforming relation to the forms, the gage plate will have been rocked downwardly about the pivot 50 until it becomes positioned relatively to the lower forms, as illustrated in Fig. 3. The width of the gage plate flanges 80 is sufficiently less than the original thickness of the sole to allow for such compression of the sole as may take place and to insure that the presence of the flanges between the molding forms will not interfere with the molding operation. As the lower form 16 is being lowered, after the molding of the sole has been completed, the spring finger 72 will react to return the gage plate to the elevated position relatively to the lower form which it normally occupies.

The width of the flanges on the gage plate 70 and of the flange on the spring finger 72, and the normal positions of these flanges heightwise of the form 16, are such, relatively to the average thickness of the heel portions of the soles to be operated upon, that in most instances the flanges of the gage plate will engage the sole edge throughout a portion, at least, of the full thickness of the sole and thus will function in positioning the sole in the desired angular as well as the desired longitudinal relation to the form. In some cases, however, the heel end of the sole may be disposed at such an elevation that it will engage only the flanges of the gage plate 70 and in such cases, of course, the spring finger will perform no gaging function but it will permit the gage plate to yield so that the forms can be brought into cooperative molding relation.

In presenting a sole to the lower form it may happen (as for example if the operator is grasping the sole by its toe portion) that the heel end of the sole will be positioned so low that its edge will not engage the flanges 80 of the gage plate. In such an event, however, the edge of the sole will engage the flange 82 of the spring finger 72 and this flange will then function as a gage to determine the desired longitudinal position of the sole with respect to the form. The flange 82 on the spring finger 72 will insure that in no event can a sole be forced rearwardly beneath the gage plate 70 into a position where it would be squeezed between the gage plate and the lower form during the final stage of the upward movement of the lower form.

If a sole such as the spring heel sole shown in Fig. 2 is to be operated upon, and if the sole, as shown, is in a flat condition when it is being presented to the molding machine, the heel end of the sole will be engaged by the flanges 80 and the flange 82 of the gaging device and these flanges will all function in determining the position of the sole upon the form 16. If the heel end of the sole is bent upwardly somewhat it may be engaged by only the flanges 80 of the gage plate 70. If the heel end of the sole is bent downwardly, or if the sole is held so that its heel end rests upon the upper surface of the form 16, the sole may be engaged only by the flange of the spring finger 72. In either case, however, the sole will be positioned in the proper longitudinal relation to the form by the gaging device. If the sole is engaged only by the flange 82 of the spring finger 72 when presented to the machine, the curved flanges of the gage plate 70, while not in actual contact with the sole edge, will nevertheless assist the operator in determining the desired angular relation of the sole to the form since it will be only necessary for him to see that the curved heel edge of the sole is alined with the curve defined by the gage plate flanges, in which case the sole will be properly positioned angularly with respect to the form for the performance of the molding operation.

In the use of my improved gaging device it has been found unnecessary to employ a "holddown" or clamping member to hold the sole against the lower form after the sole has been properly positioned on the form by the gaging means. Consequently the upper form does not have to be notched or recessed to receive a clamping member. The molding surfaces of both forms may therefore be made continuous throughout the full length and width of the sole and the molding will be accomplished without defacement or damage to the sole such as would result if the upper form were cut away to receive a sole clamping member.

Having described my invention, what I claim as new and desire to secure by Letters Patent of the United States is:

1. In a sole-molding machine, upper and lower molding forms relatively movable toward and from each other to mold a sole supported by the lower form with one end portion of the sole spaced above said form, a gage extending between said forms for determining the position of the sole relatively to the lower form, said gage being mounted to partake of the relative movement of the forms, and yielding means carried by said gage and engaging the lower form for holding said gage normally spaced above said form in position to engage said end portion of the sole.

2. In a sole-molding machine, upper and lower molding forms relatively movable toward and from each other to mold a sole supported by the lower form with one end portion of the sole spaced above said form, a gage extending between said forms for determining the position of the sole relatively to the lower form, and a leaf spring engaging the lower form for holding said gage normally spaced above said form in position to engage said end portion of the sole, said gage and said spring being mounted to partake of the relative movement of said forms and said spring having a sole-engaging face normally positioned below said gage to prevent the sole from being forced between said gage and the lower form.

3. In a sole-molding machine, upper and lower molding forms relatively movable toward and from each other to mold a sole between them, a

main gage for determining the position of the sole relatively to said form, said gage extending between the forms to engage one end portion of the sole in cases where the sole is supported with said portion spaced a substantial distance above the molding face of the lower form, and an auxiliary gage carried by the main gage and resting upon the lower form in position to engage said end portion of the sole in cases where it is presented at a lower elevation, said gages being relatively yieldable in the direction of relative movement of the forms to enable the forms to cooperate in the molding of the sole.

4. In a sole-molding machine, upper and lower molding forms relatively movable toward and from each other to mold a sole between them, and a gaging device comprising main and auxiliary gages extending between said forms for cooperation with one another in determining the position of a sole relatively to the lower form, said gages being normally positioned at different elevations to allow for different positions of presentation of the sole and being relatively yieldable in the direction of relative movement of the forms to avoid interference with said relative movement in the direction to effect cooperation of the forms.

5. In a sole-molding machine, a lower molding form adapted to support a sole with its heel end elevated above the molding face of the form, an upper molding form for cooperating with the lower form to mold the sole, means for moving the lower form into cooperative relation to the upper form, a gage located between said forms for determining the position of the sole relatively to the forms by engagement with one end portion of the sole, and a leaf spring secured at one end to said gage and having its opposite end resting upon the lower form for holding the gage normally above the molding face of the lower form for engagement with the edge of the heel portion of the sole.

6. In a sole-molding machine, a stationary upper molding form, a support movable toward and from said form, a lower sole-supporting form on said support for cooperating with the upper form to mold a sole, an arm fulcrumed upon said support, and a gaging device carried by said arm, said device comprising a central finger extending between said forms and engageable with the edge at the heel end of the sole and two gage faces located between said forms at a higher elevation than said finger and engageable with said edge at opposite sides of the portion engaged by said finger, said finger and said faces being relatively displaceable in the directions of movement of said lower form to avoid interference with the molding operation.

7. In a sole-molding machine, a stationary upper molding form, a support movable toward and from said form, a lower sole-supporting form on said support for cooperating with the upper form to mold a sole, an arm fulcrumed upon said support, and a gaging device comprising a rigid plate and a spring finger carried by said arm and each having a free end extending between said forms, the free end of said plate being recessed to provide gage faces for engaging the edge of the heel end of the sole at opposite sides of the center line of the sole and the free end of said finger resting upon the lower form and having a gage face for engaging the edge of the heel end of the sole between the portions engaged by the gage faces on said plate, and the free end of said finger being offset below said plate whereby the plate is supported yieldingly by said finger with the gage

faces of the plate at a higher elevation than that of the finger.

8. In a sole-molding machine having sole-molding forms movable into and out of cooperative relation to mold a sole positioned between them, a sole gaging device comprising a gage plate having sole-positioning faces for engaging one end portion of a sole at opposite sides of its longitudinal center line, and a leaf spring carried by and extending below said plate and arranged for contact with one of said forms to sustain said gage in spaced relation therefrom.

9. In a sole-molding machine, a pair of relatively movable molding forms adapted to mold a sole between them, a gaging device for locating the sole with respect to one of said forms, said device comprising an end gage spaced from one of said forms and having sole-engaging faces spaced from each other for engaging the sole edge at opposite sides of the center line of the sole, and a gage located between the said sole-engaging faces, having a sole-engaging face normally offset from said spaced sole-engaging faces and yieldingly sustained to enable it to assume a position in the plane of said spaced sole-engaging faces in response to heightwise pressure of said forms.

10. In a sole-molding machine, upper and lower molding forms movable toward and from each other to mold a sole supported by the lower form, a gage plate pivoted at one end for upward and downward movements between said forms and having at its free end spaced gage faces for engaging the edge of the heel portion of the sole at opposite sides of the longitudinal center line of said heel portion, and a member yieldingly supported in the space between said gage faces forming a continuation thereof and movable heightwise relatively thereto.

11. In a sole-molding machine cooperating sole-molding forms relatively movable heightwise

to mold a sole between them, a gage, means supporting said gage for a limited amount of up-and-down movement relatively to the lower form, said gage having surfaces spaced widthwise of the sole for engaging the sole edge at opposite sides of the longitudinal center line of the sole, a leaf spring extending below the gage and having an end engaging the lower form below said gage surfaces, said spring holding said gage normally raised.

12. In a sole-molding machine, a sole-supporting form, a cooperating molding form movable relatively to the supporting form to mold a sole resting upon the latter, a gage extending between said forms, said gage having sole-engaging surfaces located at opposite sides of the longitudinal center line of the supporting form, and a leaf spring member secured to said gage and resting upon said supporting form, said spring member having a sole-edge-engaging face located between the sole-engaging surfaces of the said gage to prevent backward displacement of the sole relatively to said surfaces, said member being constructed and arranged to rest on the supporting form to hold said gage normally spaced therefrom so that it will yield when engaged by said cooperating form.

13. In a sole-molding machine, upper and lower sole-molding forms, means for moving the lower form into and out of position to cooperate with the upper form to mold a sole, a gage movable with the lower form for positioning the sole relatively thereto, said gage being pivoted at one end and having at the other end spaced portions located between said forms for engaging the edge of the heel end of the sole at opposite sides of its longitudinal median line, and a member adapted to occupy the space between said spaced portions and movable heightwise relatively thereto.

ALBIN C. EEK.
